(57) **CLAIM**

The ornamental design for an electronic device display system, as shown and described.

DESCRIPTION

FIG. 1 illustrates a first perspective view of an electronic device display system;

FIG. 2 illustrates a second perspective view thereof;

FIG. 3 illustrates a first perspective rear side view thereof;

FIG. 4 illustrates a second perspective rear side view thereof;

FIG. 5 illustrates a first perspective rear side view thereof, including additional environment shown in broken lines;

FIG. 6 illustrates a second perspective rear side view thereof, including additional environment shown in broken lines;

FIG. 7 illustrates a front elevation view of the design of FIG. 1; and,

FIG. 8 illustrates a rear elevation view thereof.

The broken line showing of the knobs and speakers in FIGS. 5 and 6 are for the purpose of illustrating environment and form no part of the claimed design.

1 Claim, 8 Drawing Sheets
